(57) CLAIM

The ornamental design for a pedal piano toy, as shown and described.

DESCRIPTION

FIG. 1 is a front, right and top perspective view of a pedal piano toy, showing my new design;

FIG. 2 is a rear, left and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is an magnified portion as designated in FIG. 1 thereof; and,

FIG. 10 is another magnified portion as designated in FIG. 1 thereof.

The long-short broken lines depict bounds and the indicia of the magnified portions and form no part of the claimed design.
